UNITED STATES PATENT OFFICE.

GEORGE D. REAGAN, OF OKLAHOMA CITY, OKLAHOMA.

HOLLOW BUILDING UNIT.

Application filed March 10, 1926. Serial No. 93,699.

My present invention is an improved form of fracturable hollow building unit of the general type shown and described in my prior Patent No. 1,495,439, dated May 27, 5 1924, and of my prior and copending application Ser. No. 674,289, filed November 12, 1923. Other forms of my novel tiles or building units are shown in my co-pending applications Serial No. 89,621 filed February 10 20, 1926, Serial No. 90,642 filed February 25, 1926, and Serial No. 93,698 filed March 10, 1926.

In my development of fracturable hollow building units formed of suitable clay and 15 in a die machine, I have developed a plurality of forms, all utilizing the features of interior pairs of cross-webs, facilitating lines of fracture between said pairs of interior cross-webs, so that each resultant sub-division 20 broken from the original unit, will itself be a complete usable unit in the resultant wall structure. Important features in the present form consist in the provision of a design of block more easily fracturable 25 with practically equal points of weakness to facilitate fracturing, together with increased strength at certain of the points of fracture, particularly on the interior lines of the cross-webs and spaces, together with 30 double webs or walls throughout both sides of the outer faces of each corner or quarter-section, and preferably also, where desired, double walls on the line of the outer face, as well as the lines of the inner faces formed 35 by fracturing or breaking the brick into sub-divisions.

In addition to these features I have devised a novel and improved form of block 40 which enables the formation on the complete block of an entire set of smooth, predetermined corners capable of enabling the sub-divided section to be used interchangeably with either the normal outer wall face of the block or one of the inner wall faces 45 of a sub-division as the finished exposed portion in the completed wall. This feature is of special importance and value and is a distinct novelty and I wish to claim the same herein broadly, resulting in a full 50 interchangeability of a sub-division of the block.

Important features and advantages consist in the arrangement of a plurality of small voids adjacent the outer wall faces of 55 the block, having the combination of such small voids at the wall faces insuring a

broad mortar bed spanning the small voids and covering at least two vertical webs for strength, and ample mortar course; providing the fracturable connections "offset" at 60 one or more points and preferably disaligned on the interior lines of fracture from the adjacent webs; forming a plurality of bracing cross members connecting the outer wall face with its next adjacent reinforcing web, 65 and thus still further insuring strength in the wall and a broad mortar retaining surface; together with a positioning of certain of the fracturable wall connections remote from certain of the corners in a sub- 70 divided portion of the unit, and also positioning the fracturable connections adjacent reinforced portions of the sub-divisions to insure breaking at the predetermined point, while also preserving the lightness, moistureproofness and heat- and cold-insulating 75 feature of a plurality of relatively large central voids or air spaces.

My several forms of improved hollow block are preferably made to fill substantially the entire thickness of a wall structure and while being relatively light, yet are so reinforced and strengthened as to give a load-carrying capacity to the hollow wall structure, together with capacity for 80 ready fracture of portions, while preserving at all times the usability of every portion broken and thus eliminating all waste, the portions fractured being themselves of so slight an extent as to be readily buried in 85 or absorbed by the normal mortar course, while adding strength to its adjacent portion.

Furthermore, my block, when sub-divided into smaller units, as for building around 90 doors, windows, corners, piers, admitting cross-beams, etc., is at once re-assembleable from a plurality of sub-divisions into substantially a unitary block structure, with practically the same strength as the original 100 unit before sub-division.

The resulting wall structure enables the strength of the combined pairs of webs adjacent each wall face to be utilized to the fullest extent, by carrying a load and with 105 the use of relatively broad mortar courses covering at least two of the webs, and a small void, space or spaces along the outer walls, thus insures ample mortar course to withstand the compressive loads of the wall, 110 it being well known that the strength of a wall depends upon the strength of the mor-

tar course. Preferably also I may form my building unit of a size to substantially simulate standard brick, so that the hollow wall structure will interlock with solid brick of corresponding thickness, where desired, at corners, piers, or floor levels where it may be desirable to stop the air spaces by a solid layer.

Further features of the invention, details, 10 novel combinations and advantages, will be hereinafter more fully pointed out and claimed.

Referring to the drawings, illustrating a preferred embodiment of my invention, 15 Fig. 1 is a partial perspective view of a wall structure;

Fig. 2 is a perspective view of the block shown in Fig. 1, with a quarter broken away;

Fig. 3 illustrating a block with a half 20 broken;

Fig. 4 illustrates a quarter sub-division which is still useful as a building unit;

Fig. 5 is a perspective view of a large tile, either of cubical or longer form;

25 As shown in Figs. 1, 2, 3 and 4, this block or building unit gives capacity for ready and interchangeable fracture in either cross-diameter. The block or unit, therefore, is made up in original form, with practically 30 four equal quarter sections, united by fracturable connections. Each quarter section also has preferably each outer face made of two webs with a relatively small void therebetween, thus giving capacity for broad mortar bed, which would cover both webs and 35 span the relatively small void therebetween. Designating this block generally as 1, it is formed with the outer faces of each quarter comprising the face 2 and parallel adjacent 40 web 3, with a small void 4 therebetween.

Along the adjacent front face 2 is a wall 5 in each section having a parallel adjacent web 6, with a small void 7 therebetween, and with the interior webs 8 and 9, constituting 45 one wall of the interior pair of cross-webs through which the block is broken into halves or quarters. Thus the webs 3, 6, 8 and 9 of each quarter enclose a relatively large opening or void 10. The entire block 50 is thus composed of fracturable quarters along the lines of the double interior cross-webs 8 and 9, being connected at the center by one or more fracturable connections 11, preferably offset from the webs 8, and the 55 cross-webs 9 being connected at or near the faces 5 by fracturable connections, preferably offset as illustrated at 12, thus permitting the formation of kerfs 16 having smooth predetermined corners formed thereon. It

60 will be readily appreciated that this form embodies the advantages of the double pairs of interior cross-webs, giving relatively long fracturable voids as designated at 13 and 14.

When built into a wall structure as shown 65 in Fig. 1, the double web portions 2 and 3

are preferably positioned in the outer wall face, or in parallelism to receive the comparatively broad mortar beds 20, 20, the mortar readily spanning the small voids 4 and simply "keying in" same, while thus covering 70 the two adjacent webs 2 and 3. The block 1 is preferably of suitable area to span the width of the wall, as shown, and a half block 21, as illustrated in Fig. 3 and at the corner of the top course shown in Fig. 1, can be 75 readily fractured and built in with the wall to stagger joints on the full blocks.

While I preferably utilize separated mortar beds—as shown at the right in Fig. 1—to provide moistureproofness, the large air 80 spaces 10 thus interrupting each horizontal mortar course, yet I may equally advantageously employ a practically solid mortar bed as shown at 22, at the left of Fig. 1. Thus, where greater strength is desired, or where 85 half blocks or quarter sections may be employed, it is sometimes desirable to increase the mortar bed, in which case the entire web strength of the wall structure is utilized by 90 mortar coverings, leaving only the hollow interior air openings 10. Thus the small voids in the wall faces or between the double webs of the wall face are sealed at the mortar course, whereas the large voids 10 are preferably open throughout the height of a story 95 or of the wall. Insulating material, piping, wiring, etc., may be conducted through any of these air spaces, thereby adding the provision of a cold proof, heat proof and moisture proof wall structure. Furthermore, the 100 addition of the webs 6, laterally of the wall, add greatly to the strength and load-capacity of the wall.

As illustrated in Fig. 5, a slightly modified construction is shown.

In Fig. 5 I have illustrated the present type of building block with the double wall or web structure on two faces only of the block. This block 30 is thereby provided with double webs 31 and 32 on two of the 110 faces, and the single walls 33 on the other faces, the interior pairs of cross-webs 34 and 35, respectively, constituting the pairs through which the small fracturable connections 36, and the webs 34 and 35 forming the 115 small void 37, unite the block. Additional reinforcing webs 38 are provided adjacent the interior cross-webs 34, to provide increased strength, broader mortar beds and the like advantages. Further bracing cross-webs 39 are provided between the webs 31 and 32 to give increased strength and load-resistance to the block. The use of this block 30 may be interchangeably employed either with the voids horizontally or vertically, and is of course readily fracturable 120 into halves, quarters, or three-quarter sections.

In the forms herein illustrated, I employ 125 the feature of double interior pairs of cross-

webs, with fracturable connections therebetween, thus resulting in the sub-division of usable building members from the entire unit or block. Furthermore, with the building unit thus sub-divided—where desired at beams, windows, piers, walls, or around pipes or the like, I prevent all waste by utilizing the resultant sections, and even when thus sub-divided, the sections broken can be repositioned in the wall with perfect facility and interlocking where desired. The small fracturable connections 11, 12, 43, etc., are of such slight extent that they will be readily buried within and covered by the adjacent mortar joint permitting use of the half and quarter sections interchangeably, horizontally or vertically, so far as the voids are concerned. All the different forms of blocks may be of any appropriate size or dimension, and of cubical or rectangular extent, capable of being made in an economical die machine and wire cut to length. In fact the wire cutting cross-wise of the line of travel of the column of clay material is a desirable feature, as such wire cutting will usually partially close the small voids in the wall faces, thereby preventing mortar from falling therein—other than slightly extending downwardly to key the walls and hence affording the united extent of a broad mor-

tar base of both webs and the area of the small voids. The blocks are used interchangeably, interlock completely, and fracture into subdivisions easily.

My invention is further described and defined in the form of claims as follows:

1. A rectangular hollow building block or tile, comprising double outer walls on each side, a pair of longitudinally extending interior webs terminating at opposite faces of the block in kerfs formed by offset transverse webs connecting said longitudinal webs near their outer ends, a plurality of pairs of transverse webs extending from opposite double walls and abutting against said longitudinal webs, and a pair of webs connecting said longitudinal webs adjacent to but offset from said pairs of transverse webs.

2. A rectangular hollow building block or tile, comprising double outer walls on each side, said block being divisible along distinct lines of fracture into four separable building units, each unit having two double walls and two single walls, and each unit being joined to an adjacent unit by a plurality of fracturable transverse webs.

In testimony whereof, I have signed my name to this specification.

GEORGE D. REAGAN.
